CLAIM

The ornamental design for a pad with cotton flannel top and sueded backing for protecting bed sheets from fluids and stains, as shown and described.

DESCRIPTION

FIG. 1 is a front elevational view of the pad with cotton flannel top and sueded backing for protecting bed sheets from fluids and stains showing my new design;
FIG. 2 is a rear elevational view thereof;
FIG. 3 is a right view thereof;
FIG. 4 is a left view thereof;
FIG. 5 is a top plan view thereof;
FIG. 6 is a bottom plan view thereof; and,
FIG. 7 is an enlarged view taken from the circle 7 in FIG. 1.
